UNITED STATES PATENT OFFICE.

WILLIAM L. D'OLIER, OF PHILADELPHIA, PENNSYLVANIA.

CENTRIFUGAL MACHINE.

No. 879,130.

Specification of Letters Patent.

Patented Feb. 11, 1908.

Application filed March 26, 1906. Serial No. 308,073.

To all whom it may concern:

Be it known that I, WILLIAM L. D'OLIER, a citizen of the United States, residing at Philadelphia, in the county of Philadelphia and State of Pennsylvania, have invented 5 certain new and useful Improvements in Centrifugal Machines, of which the following is a specification.

My invention relates to centrifugal separating or drying apparatus, involving the principle, well understood in the art, of separating liquids from solids, liquids from liquids, etc., by rapidly rotating the materials to be dried or separated.

It is the object of my invention to provide 15 an efficient and compact arrangement of centrifugal machine which may be conveniently driven by steam, or any suitable motor, there being provided for use when desired a 20 heating chamber surrounding the usual curb, such heating chamber having steam circulating therethrough or containing an electrical heater or provided with any other heating agency.

It is the object of my invention to provide 25 in a steam driven machine, means for heating the contents of the centrifugal basket and allowing the steam, either live or exhaust, to pass out through a hollow shaft upon which 30 the centrifugal basket is mounted.

My invention resides also in other features hereinafter described and pointed out in the claims.

For an illustration of one form my invention may take, reference is to be had to the accompanying drawing.

A pedestal 1, preferably of cast iron, has 40 secured to its top, by bolts 3, 3, a casting of sheet metal curb member 4 provided with an inner wall plate 5 forming the curb proper surrounding the centrifugal basket 6. This basket is secured by a taper fit upon the upper end of the hollow shaft 7 by means of the perforated cap 8 which is screw threaded 45 and engages the screw threads at the upper end of the shaft 7. The shaft 7 has upon it at its lower end, the collar or shoulder 9 resting upon the superposed washers 10, 11 and 12 resting upon the casting or plate 13 50 secured by bolts 14, 14 to the lower end of the hanger 15 secured by bolts 16, 16 to the underside of the top plate 2 of pedestal 1. The hanger 15 is bored out and babbitted as shown at 17 to form a bearing for the outside 55 of the hollow shaft 7. In the compartment 18 between the casting 4 and plate 2 and

mounted upon the hollow shaft 7 is the steam turbine wheel 19 the steam for which is supplied by a nozzle 20 forming a continuance of the steam pipe joint 21. A stuffing box 60 or gland 22 is provided in the bottom of the curb chamber to accommodate the passage therethrough of the hollow shaft 7.

Extending well up into the inside of the hollow shaft 7 is the pipe 23 which is screw 65 threaded into the member 13 and has an elbow or other convenient joint 24 for attachment of a suitable pipe leading away from the machine.

Small lengths of exteriorly screw threaded 70 pipes 25 and 26 communicate between the turbine wheel and compartment and the curb chamber and heating chamber respectively. These short lengths are accessible by hand holes having suitable covers 27, and 75 are provided with caps 28 which may be interchanged in any suitable combination as hereinafter described.

The casting 13 has an oil tight joint with the member 15 so that the washer bearing of 80 the hollow shaft is maintained flooded with oil which stands in the bearing 17 and fills more or less of the depression or reservoir 15' in the top of the member 15.

The operation is as follows: The steam is- 85 suing from the nozzle 20 strikes the blades of the turbine wheel 19 and thereby rotates the basket 6 and its contents at a high rate of speed. The exhaust steam from the turbine may, when the caps 28 are on the short pipes 90 26, (thus cutting off communication with the heating chamber 4') pass through the short pipes 25 into the curb chamber, which is closed by the cover 29, thus heating the perforated basket wall 6 and thence passing 95 through the top of the basket into the interior thereof to further heating the contents and thence passing through the perforated cap 8 through the hollow shaft 7 and thence through the exhaust pipe 23 to some external point. The pipes 25 and 26 may be open 100 at the same time thus allowing a portion of the steam to pass as just described, while a portion will pass into the heating chamber 4' and out through exhaust port 30. Or the 105 short pipes 25 may be closed by caps 28, and all of the exhaust steam may pass into the heating chamber 4' and thence through the exhaust opening 30. When the heating agent is passing through or inclosed in the 110 heating chamber 4', heat is communicated through the curb wall 5 to the interior of the

curb and through the perforated wall 6 of the basket and its contents. Or the turbine may exhaust directly to the outer air and live steam may be employed in either or both 5 the curb chamber or the heating chamber 4'. If desired the heating chamber 4' may be omitted, and the compartment 18 also.

In place of using steam as the heating agent in the chamber 4', an electric heater 10 may be inclosed therein if desired, or any other source of heat may be employed. The liquid thrown through the perforations of the wall 6 of the basket is collected on the bottom of the curb and carried away by the 15 pipe 31. The level of the outlet pipe 31 in the curb 5 should be lower than the top of the short pipes 25, to insure that none of the separated liquid will pass into the turbine chamber 18.

20 What I claim is:—

1. In combination, a rotatable hollow shaft, a centrifugal basket secured thereto, a perforated cap within the basket and secured upon said shaft, means for admitting a 25 heating agent to said basket, and a pipe extending into said hollow shaft, whereby said heating agent may pass out through said cap, hollow shaft and pipe.

2. In combination, a rotatable hollow 30 shaft, a centrifugal basket secured thereto, a perforated cap secured upon said shaft within said basket, an exhaust pipe communicating with said hollow shaft, a steam motor driving said hollow shaft, and means for admitting exhaust steam from said motor to 35 said basket, said steam adapted to heat the contents of the basket and to pass out through said cap, hollow shaft and exhaust pipe.

40 3. In combination, a rotatable shaft, a centrifugal basket secured thereto within a curb chamber, the rotatable element of a fluid motor secured upon said shaft in a chamber independent of said curb chamber, 45 and means for permitting escape of exhaust fluid from said motor after passing through said basket.

4. In combination, a hollow rotatable 50 shaft, a centrifugal basket secured thereto within a chamber, the rotatable element of a fluid motor secured upon said shaft in a chamber independent of said chamber surrounding said basket, means for admitting a heating agent to the basket chamber, and 55 means permitting the exit of said heating agent through said hollow shaft.

5. In combination, a rotatable hollow 60 shaft, a centrifugal basket secured thereon, the rotatable element of a fluid motor secured upon said shaft, and means for directing exhaust fluid from said motor through said basket and through said hollow shaft.

6. In combination, a centrifugal basket, 65 a rotatable hollow shaft supporting said basket and opening into the same, means for

admitting heating fluid to said basket, and a fluid tight connection with said rotatable shaft, whereby said heating agent may pass out through said shaft.

7. In combination, a centrifugal basket, a 70 rotatable hollow shaft supporting said basket and opening into the same, means for admitting heating fluid to said basket, and a pipe extending into said hollow shaft through a fluid tight connection, whereby said heating fluid may pass out through said shaft and pipe.

8. In combination, a hanger, a rotatable hollow shaft having an end bearing in said hanger, said bearing inclosed in a fluid tight 80 compartment, a centrifugal basket supported by said shaft and into which said shaft opens, and a stationary pipe extending through said bearing compartment into said shaft, whereby said pipe communicates with 85 the interior of said basket.

9. In combination, a pedestal, a vertically disposed hanger suspended therefrom, a hollow shaft having an end bearing in said hanger, said bearing being inclosed in a fluid 90 compartment, a centrifugal basket supported by said hollow shaft and into which said shaft opens, means for admitting a heating agent to said basket, and a pipe extending into said hollow shaft, whereby said 95 heating agent may pass out from said basket through said shaft and pipes.

10. In combination, a rotatable hollow shaft, a centrifugal basket secured thereto and into which said shaft opens, means for admitting heating agent to said basket, and a stationary pipe extending into said hollow shaft, whereby said heating agent may escape through said pipe and shaft.

11. In combination, a pedestal, a hanger 105 suspended therefrom, a hollow rotatable shaft having a bearing in said hanger, the rotatable element of a fluid motor secured to said shaft within a chamber, a centrifugal basket secured upon said shaft in a chamber 110 independent of said motor chamber, the bore of said hollow shaft communicating with the interior of said basket, means for admitting exhaust fluid from said motor to said basket, and a pipe extending into said hollow shaft, 115 whereby said exhaust fluid may pass from said basket through said shaft and pipe.

12. In combination, a pedestal having a top plate, a superposed member forming with said plate a chamber, a hanger suspended 120 from said plate, a rotatable shaft having a bearing in said hanger, the rotatable element of a fluid motor secured upon said shaft in said chamber, a centrifugal basket secured upon said shaft in a chamber independent of 125 said motor chamber, and means for admitting exhaust fluid from said motor into said basket chamber.

13. In combination, a centrifugal basket within the chamber, a shaft supporting the 130

same, the rotatable element of a fluid motor secured to said shaft, and a second chamber surrounding said basket chamber, and means for admitting exhaust fluid from said motor to either or both chambers.

14. In combination, three chambers, a centrifugal basket disposed in one chamber, a shaft supporting said basket, the rotatable element of a fluid motor secured to said shaft 10 in another chamber, the third chamber sur-

rounding said basket chamber, and means for admitting exhaust fluid from said motor to either or both of the other chambers.

In testimony whereof I have hereunto affixed my signature in the presence of the two 15 subscribing witnesses.

WILLIAM L. D'OLIER.
